UNITED STATES PATENT OFFICE.

ARTHUR R. KRAUSE, OF WOODHAVEN, NEW YORK, ASSIGNOR TO THE LION ELECTRIC MANUFACTURING CO. INC., A CORPORATION OF NEW YORK.

LIGHTING FIXTURE.

Application filed May 2, 1925. Serial No. 27,446.

The present invention relates to lighting fixtures and is more particularly directed to bracket-type fixtures of a form more especially suited for candle-type lamps.

According to the ordinary construction of lighting fixtures of this type it is customary to employ a back plate and a number of arms which are attached to the back plate and which support the lamps. These arms are made hollow or are provided with channels so as to conceal the lead in wires or are made out of bent straps, with or without ornamental leaves, or the like. Quite a large number of parts are required, which add to the expense of construction, and considerable skilled labor is required for assembling these numerous parts. These arms have made it difficult to provide wall brackets having architectural effects.

The present invention contemplates a wall bracket lighting fixture in which the candles are carried and supported in such a manner that the fixture may be easily assembled, and in such that the lead wires may be satisfactorily concealed in a simple manner.

The invention also preferably contemplates the provision of a lighting fixture which utilizes a back plate and a balcony shaped platform member carried below and in front of the back plate, and from which candles are supported, there being a suitable rail or rim about the balcony to hide or conceal the candle support. For example, the fixture may have a wall plate provided with columns designed to cooperate with the balcony design in a pleasing manner.

Another object of the invention is to provide a lighting fixture which may be conveniently made up out of cast parts, such as white metal castings, which are so shaped that they may be soldered together to provide the ornamental parts of the fixture, and in which the electrical parts of the fixture may be readily installed and concealed.

Other and further objects of the invention will appear as the description proceeds.

In the accompanying drawings there are shown for purposes of illustration, two of the many possible forms in which the present invention may be embodied, surface ornamentation being omitted, it being understood that the forms shown in the drawings are merely illustrative of the invention which may be embodied in numerous forms.

In these drawings:—

Figure 1 is a perspective view showing the back plate, and lower part of the fixture separated from another, and placed so as to show the mode of assembling the fixture; 60

Figure 2 is a side elevational view of the fixture with parts in section; and

Figure 3 is a fragmentary sectional view of a slightly modified form of construction.

The back plate 10, may have any suitable configuration, and is here shown as being in the form of a casting of generally rectangular configuration and provided with an ornamental outline. The casting may be made of any suitable material such as white 70 metal, bronze, brass or other suitable materials. It is preferably made to have an artistic outline and is also preferably provided with suitable surface ornamentation to enhance its artistic value. As an example 75 for such design suitable for a wall bracket I would refer to Letters-Patent for Design for lighting fixtures Number 67,664, granted June 23, 1925.

As shown in the drawings this back plate 80 10 is preferably recessed as shown at 11 to lighten the structure. This recess may be made by recessing the pattern, or where white metal slush castings are used, the recess may be provided in the usual manner. This 85 recess provides the space for attaching the usual supporting straps, not shown. The lower end of the back plate casting is provided with a transverse wall 12, which preferably has a plain smooth surface which extends across the entire lower end of the back plate. 90

A balcony member 13, also in the form of a casting is of the proper size and configuration to fit the lower end of the back plate 95 and to extend downwardly some distance along the wall, and also in front of the back plate sufficiently to carry the candles. The lower end of the back plate, and the upper back part of the part 13 may have various 100 cooperative configurations suitable to permit fastening the parts together. This will depend to some extent upon the material used, the form and configuration of the parts, and the ornamental design of the fixture. 105

As here shown the upper rear corners of the casting 13, are cut away as indicated at 14 and 15 to provide smooth upper surfaces 16 which are adapted to fit the lower surface of the bottom wall 12. 110

The cut away portions 14 and 15 are also provided with vertical surfaces 17-17 of the proper shape to fit the front surface 18, of the wall plate. Inasmuch as the form of design utilized in the wall plate here illustrated requires an outwardly projecting band 19, to form a base for the columns at the side edges of the wall plate, the lower part 13 is provided with slots 20 to permit the bringing of the surfaces 17 and 18 together.

The upper part of the balcony 13 is also provided with a peripheral rail or rim 21, which is adapted to extend from one of the surfaces 17 around the front of the casting to the other surface 17. A narrow shelf 22, is provided a short distance below the upper edge of the rim, and a plate 23 is fitted on this shelf inside the rim of the casting. This plate is provided with holes 24 suitably placed to carry the candle or candles with which the fixture is to be provided, nuts 25 are soldered to the under side of the plate, a hole in each nut being underneath the hole 24. The plate 23 is here shown as being soldered in place on the flange or shelf 22 by applying drops of solder 26, suitably located to accomplish the purpose. In this manner the plate and bottom casting 13, may be readily fastened together.

The bottom casting 13 and plate 23 may then be mounted on or attached to the back plate 10, by placing the parts in the proper position and then soldering them together as indicated at 28 and 29. This provides a rigid, solid fixture which may be handled as a unitary structure. In designing the fixture the parts are preferably so shaped and ornamented that no parting line appears between the various parts of the fixture when viewed from ordinary angles.

After the parts have thus been soldered, a threaded sleeve or nipple 27, is passed through the hole 24 and threaded into the nut 25, and on this sleeve one mounts a candle socket in the usual manner. The lead wires 30 are passed, down through the nipple and out through the chamber 31, provided by the casting 13, to the rear of the fixture where they are connected to the house wires in the usual manner. The usual candle sleeve 32, the lamp 33, are provided to complete the fixture.

In making up a fixture the parts 10, 13 and 23 are preferably soldered together as a unit and then subjected to any plating or spraying operations that may be desired in finishing the fixture. It is of course possible to perform plating or spraying operations on the separate fixture parts before they are assembled.

Fixtures made in accordance with the present invention may effectively conceal the lead in wires and electrical mechanism.

The mode of construction is not at all obvious to the ordinary observer, and on account of configuration preferably given to the parts, the support for the candles is concealed when a fixture is mounted above the ordinary line of vision. It will also be noted that the fixture may be readily assembled out of castings, the only operations necessary being soldering or otherwise fastening of the parts together.

While soldering is the preferable method of fastening the parts together when the materials used permit it, it is sometimes desirable to make fixtures of this type out of materials which will not solder readily. In this case one may use the construction shown in Figure 3. Here the bottom of the part 34 is fastened to the wall plate 35 by means of screws 36, and the plate 37 is fastened on the shelf 38 of the bottom part 34 by means of screws 39. Other methods of fastening the parts together will of course readily suggest themselves to those skilled in the art.

It is obvious that the invention may be embodied in many forms and constructions, and I wish it to be understood the particular forms shown are but a few of the many forms. Various modifications and changes being possible, I do not limit myself in any way with respect thereto.

What is claimed is:—

1. A lighting fixture back plate, a bottom member carried underneath the lower end of the back plate and having a lower wall extending forwardly thereof, a shelf carried within said bottom member and spaced above the lower wall thereof, and an electric candle mounted on the shelf and extending upwardly in front of the back plate.

2. In a lighting fixture of the wall-bracket type, a member having a horizontal rim about the upper front part thereof, a plate carried inside said rim, an electric lamp supported on top of the plate, the member and plate providing a chamber for lead wires, and a wall plate attached to the upper rear part of the member.

3. In a lighting fixture, a wall plate, a bottom member which extends below the plate and in front of the lower end of the plate to conceal the same, the upper front part of said bottom member being provided with an inwardly directed shelf spaced below the upper edge thereof, a second plate supported on said shelf, an electric lamp carried by the second plate in front of and spaced from the wall plate, and means of fastening the bottom member to the wall plate.

4. In an electric lighting fixture of the wall-bracket type, two castings fastened together, one of the castings having a lamp supporting plate carried therein and normally concealed, and an electric lamp carried

on said plate in front of the other casting, said first mentioned casting being shaped to cover the lower end of the other casting and to provide a rearwardly opening chamber for the lead wires for the lamp, the back walls of the castings being in the same plane so that the fixture may be mounted on a wall.

5. A balcony member for lighting fixtures of the wall-bracket type, said member having a closed bottom and an upper peripheral rim extending from one rear corner of the mem-

ber around the front of the member to the other rear corner, and a lamp supporting plate carried inside the rim and spaced above the bottom of the balcony, the balcony member having rearwardly extending depressed areas at the corners for cooperation with an upwardly extending wall plate, and a wall plate attached to the balcony member, the back of the balcony member and of the wall plate being in the same plane to facilitate hanging the bracket on the wall.

ARTHUR R. KRAUSE.
